CIGARETTE AND MATCH CASE

Ambrosio Arce, Dagupan, Pangasinan, P. I.

Application October 25, 1935, Serial No. 46,815

2 Claims. (Cl. 206—38)

This invention relates to cigarette and match cases, and has for its object the production of a simple and efficient cigarette case which is so constructed as to conveniently sit up in an open position so that cigarettes may be easily and conveniently removed from the case and burned matches deposited within a suitable compartment formed within the case.

A further object of this invention is the production of a simple and efficient cigarette case preferably formed of metal or other similar material, the case consisting of a container which is pivotally mounted within a frame, the frame and container being capable of being swung at an angle relative to each other and locked in this position whereby the container may be conveniently supported in an open position.

Other objects and advantages of the present invention will appear throughout the following specification and claims.

In the drawing:—

Figure 1 is a perspective view of the cigarette case, a portion of the frame being shown in section;

Figure 2 is a perspective view of the cigarette case in its open position shown resting upon a support;

Figure 3 is a vertical sectional view through the cigarette case;

Figure 4 is a horizontal sectional view taken on line 4—4 of Figure 3;

Figure 5 is a vertical sectional view through the cigarette case the frame being shown swung to an open position for uncovering the open end of the cigarette container;

Figure 6 is a section taken on line 6—6 of Figure 2 showing the interlocking means for holding the container and frame in an open position.

By referring to the drawing, it will be seen that A designates the outer supporting frame which is preferably of a square or rectangular structure having a downwardly bent or folded abutment flange 11 along the top edge and upon one side, as indicated clearly in Figures 1 and 3.

The frame A comprises side members 12 and top and bottom members 13 and 14 respectively. The top and bottom members 13 and 14 are slightly inclined toward the side edge in the horizontal plane or are slightly inclined downwardly from their outer edge in the direction of the abutment flange 11 previously described.

A container B is pivotally mounted between the side members 12 upon the pivot bolts 15, and this container B is preferably formed from a blank sheet of material comprising a bottom 16 and

front and rear walls 17 and 18 respectively. The front and rear walls 17 and 18 are provided with overlapping flanges 19, as shown clearly in Figure 1, and the pivot bolts 15 extend through the side members 12 and also through the overlapping flanges 19, as shown in Figure 4, as well as in detail in Figure 6, the bolts 15 carrying nuts 20 for holding the bolts in place and also permitting the tension of the flanges to be increased or decreased as will be hereinafter described. 10 These flanges 19 because of their overlapping relation will constitute a spreading spring-like action to tend to hold the container B in a set position within the frame A. It should be noted that the overlapping flanges 19 will provide an efficient frictional gripping action against the side members 12 through the medium of the outwardly punched tits 21 formed in the flanges 19, as shown in Figure 6. The side members 12 are also provided with outwardly punched tits 22 20 which are adapted to be interlocked with the tits 21 when the container B is swung to the position shown in Figure 2, thereby holding the container B at an angle to the frame A in substantial X-like formation, and in this manner provide an efficient support for the container B when in an open position and supporting the container B in this position against accidental displacement. The tension of the outwardly struck tits or knobs 21 and 22 may be increased or decreased by tightening the nuts 20 upon the bolts 15 should sufficient tension fail to produce the desired locking action upon the interlocking tits 21 and 22.

When the container B is swung to a closed position, such as is shown in Figure 3, the abutment flange 11 will limit the swinging movement of the container B and constitute a stop to hold the container B in a closed position. The inclined relation of the walls of the top and bottom members 13 and 14 will facilitate the swinging of the container B to and from an open position with the frame A.

A suitable match scratching pad 23 may be supported upon the outer face of the container B within the supporting frame 24. The container B is also provided with a partition 25, which partition is provided with a square frame-like folded portion 26 at its bottom to constitute a rest for burned matches. The partition 25 will divide the container B into a cigarette containing compartment 27 and a match containing compartment 28.

It should be understood that the present cigarette case so described, may be used for supporting cigars or other articles without departing from the spirit of the invention, and it is not

desired to limit this invention to merely a cigarette case.

Certain detail changes in the mechanical construction, combination and arrangement of parts may be employed without departing from the spirit of the invention so long as such changes fall within the scope of the appended claims.

Having described the invention, what is claimed as new is: —

- 10 1. A device of the class described comprising a frame consisting of a pair of side members and a top and bottom member, a container formed from a sheet of material and consisting of a bottom and a front and rear section, the front and rear sections having overlapping side flanges normally exerting an outwardly expanding pressure, pivot bolts for pivotally securing the container and frame together and extending through the side members and through the flanges, and interfitting tits punched in the flanges and side members and adapted to interlock when the container is swung at an angle with respect to the frame for holding the container in a set angularly adjusted position with respect to the frame whereby the container and frame may assume an X-like formation, the bottom of the frame and

bottom of the frame and container constituting a means for supporting the device in an upright open position.

2. A device of the class described comprising a frame consisting of a pair of side members and a top and bottom member, a container formed from a sheet of material and consisting of a bottom and a front and rear section, the front and rear sections having overlapping side flanges normally exerting an outwardly expanding pressure, pivot bolts for pivotally securing the container and frame together and extending through the side members and through the flanges, interfitting tits punched in the flanges and side members and adapted to interlock when the container is swung at an angle with respect to the frame for holding the container in a set angularly adjusted position with respect to the frame whereby the container and frame may assume an X-like formation, the bottom of the frame and container constituting means for supporting the device in an upright open position, and adjustable nuts carried by the bolts for providing means for regulating the tension of the flanges to provide efficient gripping action between the tits. 20 25
